(57) **CLAIM**

The ornamental design for a wristband dispenser, as shown and described.

DESCRIPTION

FIG. 1 shows a front view of a wristband dispenser;
FIG. 2 shows a rear view of wristband dispenser of FIG. 1;
FIG. 3 shows a top view of the wristband dispenser of FIG. 1;
FIG. 4 shows a bottom view of a wristband dispenser of FIG. 1;
FIG. 5 shows a left view of the wristband dispenser of FIG. 1;
FIG. 6 shows a right view of the wristband dispenser of FIG. 1;
FIG. 7 shows a front perspective view of a wristband dispenser of FIG. 1;
FIG. 8 is a front view of the band portion of wristband dispenser shown separate to show detail;
FIG. 9 shows a rear view of the band portion of FIG. 8;
FIG. 10 shows a top view of the band portion of FIG. 8;
FIG. 11 shows a bottom view of the band portion of FIG. 8;
FIG. 12 shows a left view the band portion of FIG. 8;
FIG. 13 shows a right view of the band portion of FIG. 8;
FIG. 14 shows a front perspective view of the band portion of FIG. 8;
FIG. 15 is a front view of cap portion of the wristband dispenser shown separate to show detail;
FIG. 16 shows a rear view of the cap portion of FIG. 15;
FIG. 17 shows a top view of the cap portion of FIG. 15;
FIG. 18 shows a bottom view of the cap portion of FIG. 15;
FIG. 19 shows a left view the cap portion of FIG. 15;
FIG. 20 shows a right view of the cap portion of FIG. 15;
and,
FIG. 21 shows a front perspective view of the cap portion of FIG. 15.
